ANCHOR

Henry G. May, Jr., 212 S. Main St., Irving, Tex.

Filed July 1, 1960, Ser. No. 61,182

Term of patent 14 years

(Cl. D71—1)

FIGURE 1 is a front elevational view of an anchor, showing my new design;

FIGURE 2 is a side elevational view of the same;

FIGURE 3 is a bottom plan view thereof;

FIGURE 4 is a top plan view thereof.

I claim:

The ornamental design for an anchor, as shown.
